SELDEN H. HALL, OF POUGHKEEPSIE, NEW YORK, ASSIGNOR TO THE DE LAVAL SEPARATOR COMPANY, OF NEW YORK, N. Y., A CORPORATION OF NEW JERSEY.

SEALING DISCHARGE-PASSAGES OF CENTRIFUGALIZING-MACHINES AND THE LIKE.

1,149,578.

Specification of Letters Patent. Patented Aug. 10, 1915.

Application filed January 28, 1914. Serial No. 814,881.

To all whom it may concern:

Be it known that I, SELDEN H. HALL, a citizen of the United States, residing at Poughkeepsie, county of Dutchess, State of New York, have invented certain new and useful Improvements in Sealing Discharge-Passages of Centrifugalizing-Machines and the like; and I do hereby declare the following to be a full, clear, and exact description 10 of the invention, such as will enable others skilled in the art to which it appertains to make and use the same.

In an application for Letters Patent of the United States, Serial No. 756,835, filed 15 March 26, 1913, I have described and claimed certain provisions for sealing the discharge passages of centrifugalizing machines and the like against the ingress of air, which would otherwise be entrained by 20 what might be called the injecting action of the centrifugalizing liquid as it leaves the bowl and enters the annular collecting passage designed for its reception. In order to prevent the drawing in of the air by the 25 escaping force of the centrifugalized liquid as it leaves the bowl, the receiving passage is provided with a narrow annular mouth and trough, which is directly opposite to and in close proximity to the discharge 30 mouth of the bowl and the discharge mouth of the bowl rotates within an annular chamber which is in open communication with the annular trough of the receiving passage, so that by setting up a back pressure in the 35 receiving passage, a permanent liquid seal of the centrifugalized liquid will exist at all times in the annular chamber against the ingress of air therethrough. In constructions of this kind, it is desirable that the rotating discharge elements of the centrifugalizing machine should move with the least 40 allowable clearance with respect to the stationary annular sealing chamber, in order that the seal shall be permanently effective as 45 against fluctuations in the pressure conditions and other incidents of the centrifugalizing operation. In the centrifugal machines, however, particularly those of the milk clarifier type, there is always the danger that by 50 reason of wear of the step-bearing or accident thereto, the rotating parts will drop to a lower position than the normal, thereby bringing the lower surface of the rotating discharge element of the machine into contact 55 with the adjacent shelf or bottom of the

annular sealing chamber, with results which might be disastrous at the high speeds used in this class of apparatus, especially as the entire weight of the bowl with its driving apparatus would come upon the shelf or bottom of the annular chamber in such case.

Safety requires that the clearance be much greater than is necessary from the sealing standpoint, but it is also desirable, as indicated, to provide the least allowable clearance consistent with safety.

It is the purpose of the present invention to realize this result, and, at the same time, to simplify the construction of the elements constituting the seal and to render their operation more effective.

In the accompanying drawing,—Figure 1 represents, partly in section and partly in elevation, the upper body portion and neck of a rotatory centrifugalizing machine, embodying the present improvements; Fig. 2 represents a bottom plan view of the telescoping member of the rotatory sealing device; Fig. 3 represents a bottom plan view of the cover plate constituting one of the 80 elements of the discharge passage of the bowl; and Fig. 4 represents a fragmentary view of one of the elements of the bowl discharge.

Similar letters of reference indicate similar parts throughout the several views.

Referring to the drawing, A indicates a centrifugalizing bowl, as, for instance, the bowl of a milk clarifier, and B indicates the stationary casing thereof. The bowl is 90 adapted to rotate, upon a step-bearing, or the like, in a vertical position, and is provided with a hollow shaft R extending up from the bottom of the bowl and rotating therewith.

The bowl A has a contracted neck V as is usual in milk clarifiers, and, on the outside of the neck is formed a shelf c for the reception of a packing ring e. Upon the ring e rests an annular member D having an overhang d, which carries an annular sealing ring consisting of a ring base u and a cylindrical flange v. The upright flange v is secured to the overhang d, by means of pins w, which engage in bayonet joint 100 grooves x. The annular member D is forced down upon the packing ring e by spacers y z (see Fig. 3), on the underside of an annular cover plate F having a screw-threaded hub which engages with correspondingly 105 screw- 110

threads on the central tubular shaft R of the bowl.

On the upper end of the casing H is secured an annular member I, constituting a portion of the receiving passage or chamber. Resting upon the outer rim of the member I and held thereto by a clamping ring L is the filling or feed receptacle M, the bottom of which is shaped to complete the configuration of the annular receiving passage or chamber, this passage or chamber being of any suitable or approved configuration appropriate to the particular conditions of use. Leakage from the receiving chamber, at the joint between the member I and the bottom rim of the vessel M is guarded against by the interposition of the packing ring n. The filling vessel or feed receptacle M is provided with a discharge spout O which enters the central tube of the centrifugal. For the purpose of controlling the pressure within the receiving passage or chamber, the discharge conduit P leading therefrom is provided with a controlling valve R, as shown.

The overhang d projects over the vertical annular wall a of a sealing chamber, which wall projects from the inner edge of a horizontal shelf b. Both the wall a and the shelf b may be cast integral with the annular member I.

It will be noted that when the construction as above described, is adopted, the centrifugal has a narrow annular discharge throat, which is located opposite a similar narrow annular receiving throat of the chamber or passage X, so that the former discharges directly into the latter; and that the rotatory parts of the sealing device rotate within an annular chamber whose roof is the bottom of the vessel M and whose bottom is the horizontal shelf b from which the cylindrical wall a rises.

In order to make it safe to operate the machine with very small clearance between the bottom of u and the top of the shelf b, the member u is, by means of the flange v made to partially telescope over the overhang d. A spring f arranged between the overhang d and the ring plate u forces them apart, but the inwardly projecting pins w engaging the bayonet grooves x, as hereinbefore referred to, prevent separation beyond a predetermined distance. The spring f is so flexible that, in case of accident to the step-bearing of the bowl shaft, or wear thereof, of such a character as to allow the bowl to drop sufficiently to bring the lower surface of the ring plate u into contact with the upper surface of the shelf b, the spring will yield sufficiently to permit the ring u and the overhang d to approach each other, so that the pressure of u against b will be so slight as to cause no damage.

The mode of operation of the device is as

follows: The liquid to be treated is supplied to the feed vessel M and passes thence through the tube O into the bowl A. After treatment, the liquid rises in a thin layer inside the neck V of the centrifugal, and entering the narrow throat between the lower surface of the cover plate and the upper surface of the overhang d, it is discharged at great velocity into the narrow mouth and throat of the annular receiving passage or chamber X. The liquid thus passing into the receiving vessel tends to draw in the surrounding air, but, by manipulating the controlling valve R in the discharge conduits P, or by the discharge 80 against a hydraulic head, or by other approved means, a back pressure is created in the passage or chamber X, which has the effect of causing part of the liquid to flow back into the space between the throat of the 85 bowl and the walls of the annular chamber in which the throat revolves. An increase of the back pressure will force the liquid back over the upper surface of the cover plate F and also back over the upper 90 surface of the shelf b. The passage of the liquid back over the upper surface of the plate F would do no harm because it would flow back into the bowl, and leakage by the outflow of liquid over the shelf b may be 95 prevented by making use of the centrifugal force with suitable provision for utilizing the same. To this end, the under surface of the ring u and the upper surface of the shelf b should have such a configuration as to accelerate the rotary movement of the liquid in the space between them. For instance, the bottom surface of the ring u may be provided with the oblique grooves h, represented in Fig. 2. i.e., with the configuration shown, 100 and with a very small clearance between the underside of the ring u and the upper side of the shelf b there is no leak of liquid over the upwardly extending ring a at the inner edge of the shelf b, with the pressure 105 required to prevent entrance of air.

Obviously, if, for any reason, it is desired to use a higher pressure in the passage or chamber X, two or more collapsible sealing rings may be used. So also, as I have shown in the drawing, I prefer that the yielding element of the seal shall be carried by the rotating parts, (as, for instance, the ring u, by the rotating overhang d). The non-rotatory shelf b may constitute or be provided 110 with the sealing element, or both the rotating element and the non-rotating element may be provided with a yielding member, should conditions of use indicate the advisability of such construction. The fundamental or generic idea of the invention, in this respect, is to so arrange the rotatory surface and the non-rotatory surface of the sealing device that should they come in contact the one or the other, or both, will be 115 120 125 130

protected against destructive pressure, by appropriately yielding or collapsing.

What I claim is:

1. A sealing device, for preventing the drawing in of air at the liquid discharge mouth of a rotatory apparatus, said sealing device comprising a rotatory element and a non-rotatory element with an intervening liquid seal, means for yieldingly relieving the pressure of the one on the other should they come in contact, and means for setting up centrifugal force in the seal sufficient to prevent its escape inwardly.
2. A sealing device, for preventing the drawing in of air at the liquid discharge mouth of a rotatory apparatus, said sealing device comprising a rotatory element and a non-rotatory element with an intervening liquid seal, means for yieldingly relieving the pressure of the one on the other should they come in contact, said means comprising a spring seat for one of said elements, and means for setting up centrifugal force in the seal sufficient to prevent its escape inwardly.
3. Mechanism for maintaining a liquid seal, comprising a rotatory part mounted to rotate within an annular sealing chamber, said rotatory part carrying a yielding bottom plate moving in close proximity to the opposed surface of the sealing chamber and separated therefrom by a liquid-sealing passage.
4. Mechanism for maintaining a liquid seal, comprising a rotatory part mounted to rotate within an annular sealing chamber, said rotatory part carrying a yielding bottom plate moving in close proximity to the opposed surface of the sealing chamber and separated therefrom by a liquid-sealing passage, said yielding plate having likewise a circular flange encompassing the main body portion of the rotatory part.
5. Mechanism for maintaining a liquid seal, comprising a rotatory part mounted to rotate within an annular sealing chamber, said rotatory part carrying a yielding bottom plate moving in close proximity to the opposed surface of the sealing chamber and separated therefrom by a liquid-sealing pas-

sage, said yielding plate having likewise a circular flange encompassing the main body portion of the rotatory part and connected thereto by a bayonet joint.

6. A centrifugalizing bowl having a narrow annular discharge mouth, a receiving chamber having a narrow annular receiving mouth in close proximity to the discharge mouth of the bowl, an annular liquid-sealing trough communicating with said mouths, an annular overhang rotating with the bowl and dipping into said trough, and means for causing a back pressure from the receiving chamber to maintain the liquid seal.

7. A centrifugalizing bowl having a narrow annular discharge mouth, a receiving chamber having a narrow annular receiving mouth in close proximity to the discharge mouth of the bowl, an annular liquid-sealing trough communicating with said mouths, an annular overhang rotating with the bowl and dipping into said trough and carrying a yielding bottom plate, and means for causing a back pressure upon the receiving chamber to maintain a liquid seal between the yielding bottom plate and the opposing surface of the trough.

8. A centrifugalizing bowl having a narrow annular discharge mouth, a receiving chamber having a narrow annular receiving mouth in close proximity to the discharge mouth of the bowl, an annular liquid-sealing trough communicating with said mouths, an annular overhang rotating with the bowl and dipping into said trough and carrying a yielding bottom plate, said bottom plate having a configuration to accelerate the rotatory movement of the liquid between it and the opposing surface of the trough, and means for causing a back pressure upon the receiving chamber to maintain a liquid seal between the yielding bottom plate and the opposing surface of the trough.

In testimony whereof I affix my signature, in presence of two witnesses.

SELDEN H. HALL.

Witnesses:

CHARLES L. POWELL,
S. B. ROCKEFELLER

It is hereby certified that in Letters Patent No. 1,149,578, granted August 10, 1915, upon the application of Selden H. Hall, of Poughkeepsie, New York, for an improvement in "Sealing Discharge-Passages of Centrifugalizing-Machines and the Like," errors appear in the printed specification requiring correction as follows: Page 1, line 21, for the word "centrifugalizing" read *centrifugalized*; page 2, line 46, for the word "botom" read *bottom*; and that the said Letters Patent should be read with these corrections therein that the same may conform to the record of the case in the Patent Office.

Signed and sealed this 5th day of October, A. D., 1915.

[SEAL.]

R. F. WHITEHEAD,
Acting Commissioner of Patents.
